(57) **CLAIM**

The ornamental design for an aerosol delivery device, as shown and described.

DESCRIPTION

FIG. 1 is a bottom perspective view of the aerosol delivery device showing the new design;

FIG. 2 is a top perspective view of the aerosol delivery device;

FIG. 3 is another top perspective view of the aerosol delivery device;

FIG. 4 is a front elevational view of the aerosol delivery device;

FIG. 5 is a rear elevational view of the aerosol delivery device;

FIG. 6 is an elevational view of a side of the aerosol delivery device;

FIG. 7 is an elevational view of the opposing side of the aerosol delivery device;

FIG. 8 is a top plan view of the aerosol delivery device;

FIG. 9 is a bottom plan view of the aerosol delivery device;

FIG. 10 is a bottom perspective view of the aerosol delivery device showing a further embodiment of the new design;

FIG. 11 is a top perspective view of the aerosol delivery device;

FIG. 12 is another top perspective view of the aerosol delivery device;

FIG. 13 is a front elevational view of the aerosol delivery device;

FIG. 14 is a rear elevational view of the aerosol delivery device;

FIG. 15 is an elevational view of a side of the aerosol delivery device;

FIG. 16 is an elevational view of the opposing side of the aerosol delivery device;

FIG. 17 is a top plan view of the aerosol delivery device; and,

FIG. 18 is a bottom plan view of the aerosol delivery device. The broken lines shown in the drawings depict portions of the aerosol delivery device that form no part of the claimed design.

1 Claim, 16 Drawing Sheets
